Mary E. Brady, INVENTOR

BY *Victor J. Evans*

ATTORNEY

UNITED STATES PATENT OFFICE

MARY E. BRADY, OF MAUMEE, OHIO

LAMP LOCK

Application filed January 14, 1929. Serial No. 232,548.

This invention relates to locks and more particularly to a lock for electric light bulbs which will serve to lock the bulb in an operative position into its socket to prevent theft or other unauthorized removal of the same. The device is particularly well adapted for use by hotel and rooming house proprietors not only to prevent theft of the light bulbs, but to prevent their removal for the insertion 10 of other current consuming devices, such as electric irons, curling irons, electric stoves and radio equipment.

It is an object of the invention therefore to provide a device which will not only prevent unauthorized removal of a light globe from a socket, but one which is extremely simple in its construction, which is unlikely to get out of order and which is particularly well adapted to perform the services required of it.

20 With these and many other objects in view which will more readily appear as the nature of the invention is better understood, the same consists in the novel construction, combination and arrangement of parts shown in 25 the accompanying drawings, in which:—

Figure 1 is a side view of the improved lock showing the device in actual use.

Figure 2 is a side view of the lock assembly, the lock to which the same is attached being 30 shown in dotted lines.

In both of the above mentioned views, like characters of reference are employed to designate like parts throughout. The ordinary light globe is designated as an entirety at 10. This 25 globe comprises a bulb 11 formed of glass having a reduced portion 12 which has secured thereto a threaded ferrule 13 formed of copper or any metallic composition that is a conductor of electricity. This ferrule 13 40 forms a contact and is connected in any suitable manner to one end of the resistance unit, (not shown) on the interior of the light globe. Another contact is provided at 14 on the end of the reduced portion 12 and this contact is 45 connected to the other end of the resistance unit and is adapted to contact with a contact in the socket when the globe is screwed into the same.

The socket is shown at 14'. This socket 50 has a pair of wires 15 leading thereto and has

the usual switch operated by a turn button 15' resembling the shape of the ordinary wing nut. In order to prevent removal of the light globe from its socket the ferrule 13 is provided with a strip of material 16 secured to or formed integral with the same. This strip of material extends along the reduced portion 12 of the light globe and terminates in a lateral flange 17 adapted to extend outside of the socket 14 when the light globe is 55 screwed into position. The lateral strip 17 is provided with an aperture therethru and this aperture is adapted to receive a wire loop 18 which is passed around the shank of the turn button 15'. The loop 18 has its ends brought together and sealed in the usual manner with an ordinary lead seal 19 which may be pressed firmly about these ends.

It is obviously apparent that the lateral flange 17 may be treated by dipping, brushing or other well known methods of coating with a suitable non-conductive material such as rubber, porcelain, etc., whereby the hands of the person using the particular light will not be subjected to shock incident to contact with any live parts of the fixture. The latter instance is especially true where the sockets are of the pull chain or key operated types.

It will be seen from the above description that when the light is secured into its socket and the wire passed thru the aperture in the flange 17 and around the shank of the member and sealed therearound, it is impossible for the globe to be removed without detection, for if the globe is to be removed either the seal must be destroyed or the ferrule must be mutilated. It is obvious then that I have provided a device which is extremely simple in construction, and efficient in its operation. I do not desire to be limited to the exact arrangement of parts shown in the accompanying drawings, for example, the invention is not confined for use solely in connection with light globes as any electrical equipment that is provided with a threaded plug for insertion into a light socket may be insured against unauthorized removal by the application of the principle of this invention. Only in so far as the invention is particularly 100

pointed out in the accompanying claim, do I desire to be limited.

What is claimed is:—

A lock comprising a lamp socket having the shank of the switch therefor projecting for an appreciable distance therefrom, a bulb having a portion removably secured within said socket, an apertured strip carried by and outwardly projecting from the detachably secured portion of the bulb beyond the socket and aligned terminally thereof with said shank, and a seal passed through the apertured portion of the strip and looped about the shank to prevent theft of the bulb.

In testimony whereof I affix my signature.

MARY E. BRADY.
